UNITED STATES PATENT OFFICE.

EDWARD P. COLE, OF CHICAGO, ILLINOIS, ASSIGNOR TO COLE MANUFACTURING COMPANY, OF CHICAGO, ILLINOIS, A CORPORATION OF ILLINOIS.

DOOR STRUCTURE FOR HEATERS.

Application filed November 14, 1923. Serial No. 674,634.

To all whom it may concern:

Be it known that I, EDWARD P. COLE, a citizen of the United States, residing at Chicago, in the county of Cook and State of Illinois, have invented certain new and useful Improvements in Door Structures for Heaters, of which the following is a specification.

My invention has reference to a door and door casing, and seeks to provide a draft opening which may be conveniently and effectively closed.

The principal objects of my invention are to secure a permanent tight connection of a door casing with a heater casing; to provide a connection whereby a sheet metal door frame or casing may be secured directly to a sheet metal heater casing so as to provide a tight joint without the necessity of employing castings or other extra parts; to provide means for fastening a door in place against the door casing so that it closes tight thereagainst; to provide a door fastener which cooperates with a toggle hinged door to force the latter flat against the door frame and thereby insure a tight closure of the door at all points against the door casing; and in general, to provide a simple and inexpensive door and door casing structure which insures a tight closure of the draft opening into the heater.

On the drawings:

Fig. 1 is a front view of my improved door structure showing a fragmentary portion of the heater casing to which it is attached;

Fig. 2 a side view thereof with portions shown in section to disclose details of the construction; and

Fig. 3 a sectional view on the line 3—3 of Fig. 1.

Referring to the drawings, the reference numeral 1 indicates a portion of the casing of a furnace or other heater, which casing is preferably of sheet metal and formed with an opening 2 for the door casing. The door casing which is indicated at 3, is made of sheet metal, stamped in a short tubular form to fit in the opening 2 in the heater casing, and has an outturned flange 4 at the inner end which is secured against the inner surface of the casing 1 around the opening 2 by bolts 5 which are arranged at suitable intervals.

The wall of the casing 3 adjoining the flange 4 is rounded as indicated at 6 in Fig.

3, or otherwise flared somewhat so as to wedgingly engage the edge of the opening 2, as indicated in Fig. 3, when the flange 4 is clamped against the wall of the casing 1, and thereby afford a tight joint. The flange 4 is shaped to correspond to the form of the casing wall 1 around the opening 2 so as to fit flat against the casing wall, and this connection together with the wedging engagement of the curved or flared portion 6 against the edge of the opening 2 insures a joint which remains tightly closed, and is not impaired by the expansion and contraction of the heater casing 1 and the door frame 3, particularly as both of the connected parts are made of sheet metal.

The outer end of the door casing 3 is provided with a draft opening 7 surrounded by an inturned flange 8 which serves as a seat for the door 9 which closes the opening 7. The door seat or flange 8 is preferably arranged in a plane at a slight angle to the vertical as indicated in Fig. 2, so that the door which is suspended at the top, tends to close by gravity against the seat or flange 8.

For supporting the door, there is a bracket 10 directly above the door casing 3 and preferably secured in place by means of the two upper bolts 5 which serve to fasten the flange 4 to the casing 1. This bracket has a pair of laterally spaced outturned ears 11 with apertures 12 to receive the pivot lugs 13 of the link or hanger 14. This link or hanger 14, at its outer end is provided with a pair of inwardly extending pivot lugs 15 which engage in apertures 16 which are provided in spaced lugs 17 arranged on the outer face of and at the top of the door 9. The bearing apertures 12 are located above the door frame 3 and at the inner side of the plane of the seat or flange 8 so that the weight of the door tends to close the latter against the outer surface of the seat flange 8.

In view of the substantially upright position of the seat against which the door 9 closes and the comparatively light weight of the door which I prefer to employ, the door may not close by gravity sufficiently tight against the flange 8, and in order to hold the door closed and insure a tight seating of same against the flange 8, I have provided a spring latch 18 which serves to clamp the door against the flange 8. This latch 18 comprises a spring plate which is

secured at its inner end to and projects outwardly from the bottom of the door casing 3 so as to engage through a transverse slot 19 arranged near the lower extremity of the door. This plate spring 18 has the outer end bent upwardly as shown so as to ride over the lower edge of the slot 19 as the door is moved to the closed position, and has a bend 20 near the outer end arranged to provide an angular portion to engage the lower edge of the slot or notch 19 when the door is closed, so that in addition to the downward pull which is exerted on the door in the closed position of the spring 18, the latter also tends to force the lower edge of the door inwardly. By this means the door when closed is clamped tight against the outer face of the flange 8, the downward pull of the plate spring 18 serving in connection with the link 14 to force the upper part of the door against the seat 8 and the bend 20 in the plate spring serving to force the lower part of the door against the seat. The door 9 has an extension 21 below the slot 19 forming a handle or toe-hold for operating the door.

This door 9 is preferably provided with a small central opening 22 closed by a plate or valve 23 which is secured onto a threaded stem 24, which engages a threaded aperture in a rib 25 which extends diametrically across the opening 22. The stem 24 is extended beyond the outer side of the plate or valve 23 to provide a handle 26, whereby the plate and stem 24 may be rotated for clamping the edge of the plate against the opening 22 or withdrawing same therefrom.

For supporting the door in the open position there is a lug 27 on the upper edge of the door with a notch in the outer end which engages the outer end of the shell 3 at the top.

While I have shown and described my invention in a preferred form, I am aware that various changes and modifications may be made without departing from the principles of my invention, the scope of which is to be determined by the appended claims.

I claim as my invention:

1. In a heater, the combination of a door, a seat against which the door closes, means for supporting the door comprising a door hinge having a laterally shiftable axis, and a door fastener adapted to exert a tension on the door for shifting the hinge axis to clamp the door against the seat.

2. In a heater, the combination of a door, a seat against which the door closes, a door supporting link, and a spring latch for the door, said latch and link being arranged to cooperate and thereby clamp the door against the seat.

3. In a heater, the combination of a door, a seat against which the door closes, a door hanger pivotally supported at one end and

having the door hinged thereto at the other end, and a spring latch engaging the door at a point remote from the hinge connection and adapted to exert a tension on the door for simultaneously forcing the hinge edge 70 and the latch edge of the door against the seat.

4. In a heater, the combination of a door, a seat against which the door closes, a door hanger pivoted at the lower end to the top 75 of the door and pivotally supported at the upper end so that the weight of the door tends to swing the door laterally against the seat, and a spring fastener at the bottom of the door exerting a downward and inward tension on the door and cooperating with the hanger to force the top and bottom portions of the door against the seat.

5. In a heater, the combination of a door frame having an opening, a seat around the opening lying in a substantially upright plane, a door, a hanger pivotally supported above the opening and having the lower end pivoted to the top of the door with the upper and lower pivotal axes of the hanger 85 arranged in laterally spaced planes so that the weight of the door tends to hold the latter against the seat, and a spring fastener at the lower end of the door exerting a tension on the latter downwardly and laterally toward the seat.

6. In a heater, the combination of a door casing provided with an opening, a seat around the opening lying in a substantially upright plane, a bracket above the seat, a 100 door hanger pivoted to the bracket and having the lower end pivoted to the top of the door, a slot in the bottom of the door, and a plate spring engaging the slot and exerting a downward tension on the door, said spring 105 being provided with an angular portion engaging the edge of the slot so as to hold the lower portion of the door laterally against the seat.

7. In a heater, the combination of a casing having an opening through the wall, a door frame projecting through said opening and having a flaring portion wedgingly engaging the edge of the opening, and a door closing against the outer end of the door frame.

8. In a heater, the combination of a casing having an opening through the wall, an annular shell extending outwardly through the opening and having a flaring portion at the inner end terminating in an outturned flange, means for drawing the flange against the inner face of the casing wall around the opening whereby the flaring portion of the casing is wedgingly engaged 120 with the edge of the opening in the casing wall, an opening at the outer end of the annular shell having a seat therearound, and a door mounted to swing to and from the seat.

9. In a heater, the combination of a sheet metal casing having an opening therethrough, an annular sheet metal shell formed with an integral outturned flange 5 at the inner end and an integral inturned flange at the outer end and a flaring outer surface at the juncture of the first mentioned flange with the annular shell, means for clamping the outturned flange against 10 the inner surface of the casing so as to wedgingly engage the flaring portion of the shell against the edge of the opening in the casing, and a door closing against the in-turned flange at the outer end of the shell.
- 15 10. In a heater, the combination of a door, an inclined seat against which the door closes, a door supporting link hanging the door, a spring latch for the door, said latch and link being arranged to cooperate 20 and thereby clamp the door against the seat under tension at its surrounding edge.
- 25 11. In a heater, the combination of a door, an inclined seat against which the door closes, a door supporting link, a spring latch for the door, said latch and link being arranged at the side of the door remote from the link to hold the door downward and inward under tension against its seat, and means on the door to engage the seat 30 and support the door in an open position.
- 30 12. In a door structure for heaters, a casing, an inclined seat projecting from the casing, a door hanger pivoted to the casing above the seat, a door pivoted to the lower end of the hanger and adapted to normally swing against the seat, a spring latch carried by the seat and engaging the lower portion of the door to firmly hold the door against the seat, and means to hold the door in an open elevated position. 40
13. In a heater, the combination of a door, an inclined seat against which the door closes, a door hanger pivotally supported at its upper end and to which the door is pivoted adjacent the top of the seat, 45 means to clamp the door against the seat, and a notched lug on the door to engage the seat and support the door in an open position.
14. In a heater, the combination of a sheet metal casing having an opening through the wall, a sheet metal door frame projecting through said opening and having a flaring portion wedgingly engaging the edge of the opening, and a door closing against the 55 outer end of the door frame.
15. In a heater, the combination of a door, an inclined seat against which the door closes, a door hanger pivotally supported at one end and having the door hinged thereto 60 at the other end, and a spring latch engaging the door at a point remote from the hinge connection and adapted to force the door against the seat.

EDWARD P. COLE.
